his attorney.

UNITED STATES PATENT OFFICE.

ALBERT W. ALBRECHT, OF ST. LOUIS, MISSOURI.

MECHANISM FOR FORMING BALLS.

Application filed May 16, 1921. Serial No. 470,156.

To all whom it may concern:

Be it known that I, ALBERT W. ALBRECHT, a citizen of the United States, residing at the city of St. Louis and State of Missouri, have invented a new and useful Mechanism for Forming Balls, of which the following is a specification.

This invention relates to improvements in mechanism for forming balls.

10 An object of the invention is to provide a device for stamping balls out of irregularly shaped bodies.

Another object of the invention is to provide a die whereby balls may be formed by 15 a punching operation from irregularly shaped bodies.

Additional advantages will appear from the following detailed description of the invention taken in connection with the accompanying drawing, in which

20 Fig. 1 is an elevation, partially in section, illustrating the device.

Fig. 2 is a similar view illustrating the structure at the completion of the ball-forming operation.

25 As illustrated in the drawing the invention includes a die-block 1 having a cylindrical cavity 2 arranged therein. The die-block 1 is arranged to be mounted on the bed 30 of a punch press, any suitable connecting means being utilized for that purpose.

In the bottom wall of the cavity 2 is an upstanding projection 3, the upper wall of which is hollowed out to form a hemi-spherical cavity 4. An opening from the bottom 35 of the cavity 4 extends through the body of the die-block 1 and an ejector in the form of a rod 5 is mounted in said opening. The upper face of said rod has a dished portion 6 conforming to the contour of the plane of the opening into the bottom of the cavity 4.

40 A plunger 7, adapted to be mounted in the reciprocating head of the punch press, has a cavity 8 formed in the end thereof, the cavity 8 being so formed that when the end of the plunger rests in the cavity 2 and against the bottom wall thereof, the upper part of the cavity 8 will form a complete 45 spherical cavity with the cavity 4.

50 A vent opening 9, to prevent compression so that the plunger may properly seat in the cavity 2, extends from the upper wall of the cavity 8 to the side of the plunger.

55 In utilizing the device the irregularly

shaped bodies are fed into the cavity 2 in the die-block and the plunger reciprocated downwardly, the walls of the cavity 8 seating in the space between the side walls of the cavity 2 and the exterior walls of the cylindrical up-standing projection 3, thus forming the irregularly shaped body into a perfect sphere. The ejector device 5 may be operated through any suitable mechanism to force the ball or sphere out of the cavity 4 after the forming operation has been completed.

I am aware that the invention may be modified in certain particulars without departing from the spirit and scope thereof. I do not limit myself, therefore, to the exact construction shown and described, but what I claim and desire to secure by Letters Patent, is:—

1. A device of the class described, comprising a die-block having a cylindrical cavity therein, an up-standing cylindrical projection in the center of said cavity and having a hemi-spherical cavity in its upper end, and a plunger adapted to seat in said first-named cavity and having a cavity in its end to form with said second-named cavity a complete spherical cavity.

2. A device of the class described, comprising a die-block having a cylindrical cavity therein, an up-standing cylindrical projection in the center of said cavity having a hemi-spherical cavity in its upper end, and a plunger adapted to seat in said first-named cavity and having a cavity in its end to form with said second-named cavity a complete spherical cavity and having a vent opening communicating with the cavity in said plunger.

3. A device of the character described, comprising a die block having a cavity therein, an up-standing projection in the center of said cavity having a hemi-spherical cavity in its upper end, and a plunger adapted to extend into said first-named cavity and having a cavity in its lower end to receive said projection, the upper end of said last-named cavity being hemi-spherical to form with the second-named cavity a complete spherical cavity, said plunger having a vent opening from the hemi-spherical portion of said cavity in it to a point above the portion of the plunger that enters the die block.

ALBERT W. ALBRECHT.
